UNITED STATES PATENT OFFICE.

WILL R. JOHNS, OF ROCKFORD, ILLINOIS.

CARPET-FASTENER.

SPECIFICATION forming part of Letters Patent No. 284,637, dated September 11, 1883.

Application filed June 13, 1883. (No model.)

To all whom it may concern:

Be it known that I, WILL R. JOHNS, a citizen of the United States, residing in the city of Rockford, in the county of Winnebago and State of Illinois, have invented a new and useful Carpet-Fastening, of which the following is a specification.

This invention relates to fixing the edges of carpets when placed upon the floor in apartments; and its object is to provide a fastening by means of which a carpet may be readily placed in position, removed and replaced, or other carpets substituted, when required, without change of fastening; and it consists in a saw-toothed blade or blades hinge-jointed to a base-molding fixed to the base-board of an apartment, in such a manner that the teeth of the hinged blades shall engage the carpet when passed under the blades.

In the accompanying drawings I have illustrated my improvement, and have shown its application, and in which—

Figure 1 is an isometrical under edge view of my improved fastening. Fig. 2 is an isometrical view, showing its application. Fig. 3 is an isometrical view, showing the method of putting the carpet in place. Fig. 4 is an isometrical view, showing how the carpet is removed from the fastening. Fig. 5 is an isometrical representation of the stretcher.

In the figures, A represents a portion of a molding of a character suitable for a base-molding for apartments requiring a carpeted floor; but instead of the form represented any of the known forms may be employed. The back lower angle or corner of this molding is rabbed, as at a, to receive the toothed holding-plates.

At b are represented metallic plates having one edge thereof produced in saw-tooth form, and are provided at proper intervals with holes h to receive a pin or nail. These plates are placed in the rabbeted angle of the molding, having their non-toothed edge placed in the inner angle thereof, and are fixed therein to oscillate on a hinged connection by means of a pin or nail, d, driven through the molding across the inner angle of the rabbet and through the hole h in the saw-toothed plates.

At e is represented a segment or arch-formed

spring, produced in this instance from spring-wire, having its ends driven or otherwise fixed in the rabbeted portion of the molding in such position that its spring action will tend to hold the toothed plate in a vertical position against the vertical side of the rabbet a, formed in the molding. 55

At B is represented a carpet-stretcher, consisting of a handle, c, and a transverse head, K, produced from plate material, and having its front edge, n, notched in saw-toothed form to engage the carpet.

At C is represented a portion of a floor of an apartment, and at D is represented a portion of a base-board, fixed to the vertical wall 65 of the apartment and connecting with the floor. In use my improved holder is fixed to the vertical base-board of an apartment in such position thereon that the teeth of the plates will engage the floor preferably before they 70 reach a vertical position, being inclined toward the angle of the apartment produced by the junction of the base-board with the floor.

At E is represented a portion of a carpet placed upon the floor and fixed in the holder. 75

In placing the carpet in my improved holder it is spread upon the floor, having its edges placed to enter the holder. The stretcher is then placed upon the carpet, near its edge, in such a manner that its teeth shall engage or catch into the carpet, and by means of which the carpet is forced outward toward the base-board under the holder, causing the toothed plate to rise outward over or above the carpet. Then the withdrawal of the 85 stretcher will permit the toothed plate to descend by the action of the spring and engage the carpet over the teeth of the stretcher, as shown in Fig. 3, and hold it to the floor firmly. To disengage the carpet and remove it from 90 the holder, the stretcher is forced between the carpet and the holder in such a manner as to disengage the toothed plates from the carpet, as shown in Fig. 4, when the carpet can be withdrawn from under the stretcher. 95

I claim as my invention—

1. The combination, with the rabbeted molding, of an oscillating toothed plate-holder, substantially as and for the purpose set forth.

2. The combination, with the toothed hold-

100

ing-plates having a hinged connection with the base-piece, of a spring operating to hold the toothed plate in a vertical position, substantially as and for the purpose set forth.

5 3. The combination, with the base-board and with the floor, of a holder consisting of a rabbeted molding to engage the base-board, and toothed holders having a hinged connec-

tion therewith to engage and hold the carpet to the floor, substantially in the manner set forth.

WILL R. JOHNS.
